UNITED STATES PATENT OFFICE.

TAYLOR A. KALLMEYER, OF CHICAGO, ILLINOIS, ASSIGNOR TO J. MILHENING, INC.,
OF CHICAGO, ILLINOIS, A CORPORATION OF ILLINOIS.

DESIGN FOR A FINGER RING.

Application filed September 19, 1924. Serial No. 10,833. Term of patent 7 years.

To all whom it may concern:

Be it known that I, TAYLOR A. KALLMEYER, a citizen of the United States, residing at Chicago, in the county of Cook and State of Illinois, have invented a new, original, and ornamental Design for Finger Ring, of which the following is a specification.

In the accompanying drawing, forming part of this specification—

Figure 1 is a side elevation, Figure 2 an edge view, and Figure 3 a top plan view of a finger ring embodying the design.

I claim:

The ornamental design for a finger ring as shown.

TAYLOR A. KALLMEYER.
